US0D1083908S

(12) **United States Design Patent** (10) **Patent No.:** **US D1,083,908 S**
(45) **Date of Patent:** **** Jul. 15, 2025**

(54) **ELECTRONIC DEVICE**

(71) Applicant: **Getac Technology Corporation**, New Taipei (TW)

(72) Inventor: **Weisen Lu**, Taipei (TW)

(73) Assignee: **Getac Technology Corporation**, New Taipei (TW)

(**) Term: **15 Years**

(21) Appl. No.: **29/908,851**

(22) Filed: **Jan. 16, 2024**

(51) LOC (15) Cl. **14-02**

(52) U.S. Cl.

USPC **D14/341**

(58) **Field of Classification Search**

(57) **CLAIM**

The ornamental design for an electronic device as shown and described.

DESCRIPTION

FIG. 1 is a top, front, and right side axonometric view of an electronic device, showing my new design;

FIG. 2 is a bottom, rear, and left side axonometric view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of portion 9 in FIG. 2;

FIG. 10 is an enlarged view of portion 10 in FIG. 4;

FIG. 11 is an enlarged cross profile view thereof taken across line 11-11 of FIG. 4;

FIG. 12 is an enlarged view of portion 12 in FIG. 11; and, FIG. 13 is an enlarged view of portion 13 in FIG. 11.

The evenly spaced broken lines depict portions of the electronic device that form no part of the claimed design. The dot-dash broken line circles depict the limits of the enlarged views and form no part of the claimed design.
